US0D1066015S

(12) **United States Design Patent** (10) **Patent No.:** **US D1,066,015 S**
(45) **Date of Patent:** **** Mar. 11, 2025**

(54) **CONTAINER CAP**(71) Applicant: **AbbVie Inc.**, North Chicago, IL (US)(72) Inventors: **Todd Marshall**, Lindenhurst, IL (US);
Marc Plew, Gurnee, IL (US); **Ted Klikuszowian**, Arlington Heights, IL (US); **Joy Elizabeth Borgardt**, Evanston, IL (US); **James Hughes**, Libertyville, IL (US); **Kelsey M. Coffey**, Evansville, IN (US); **Scott L. Fisher**, Evansville, IN (US); **Jason A. Rowe**, Santa Claus, IN (US)(73) Assignee: **ABBVIE INC.**, North Chicago, IL (US)(***) Term: **15 Years**(21) Appl. No.: **29/943,720**(22) Filed: **May 23, 2024****Related U.S. Application Data**

(62) Division of application No. 29/721,842, filed on Jan. 23, 2020, now Pat. No. Des. 1,034,191, which is a division of application No. 29/601,290, filed on Apr. 20, 2017, now Pat. No. Des. 876,226.

CLAIM

The ornamental design for a container cap, as shown and described.

DESCRIPTION

FIG. 1 is a perspective view of a top portion of one embodiment of a container cap.

FIG. 2 is a top view of the top portion of the container cap shown in FIG. 1.

FIG. 3 is a front view of the top portion of the container cap shown in FIG. 1.

FIG. 4 is a right side view of the top portion of the container cap shown in FIG. 1.

FIG. 5 is a left side view of the top portion of the container cap shown in FIG. 1.

FIG. 6 is a rear view of the top portion of the container cap shown in FIG. 1.

FIG. 7 is a perspective view of a third embodiment of a container cap.

FIG. 8 is a top view of the container cap shown in FIG. 7.

FIG. 9 is a front view of the container cap shown in FIG. 7.

FIG. 10 is a right side view of the container cap shown in FIG. 7.

FIG. 11 is a left side view of the container cap shown in FIG. 7; and,

FIG. 12 is a rear view of the container cap shown in FIG. 7.
